[57] CLAIM

The ornamental design for a tire, as shown and described.

DESCRIPTION

FIG. 1 is a perspective view of a tire showing a first embodiment for our new design, it being understood that the tread pattern is repeated throughout the circumference of the tire, the opposite side being substantially the same as that shown;

FIG. 2 is a front elevational view thereof;

FIG. 3 is a side elevational view thereof on a reduced scale;

FIG. 4 is an enlarged fragmentary front elevational view thereof;

FIG. 5 is a perspective view of a tire showing a second embodiment of our new design, it being understood that the tread pattern is repeated throughout the circumference of the tire, the opposite side being substantially the same as that shown;

FIG. 6 is a front elevational view of FIG. 5;

FIG. 7 is a side elevational view of FIG. 5 on a reduced scale; and

FIG. 8 is an enlarged fragmentary front elevational view of FIG. 5.
